UNITED STATES PATENT OFFICE.

HENRY HIGGIN, OF NEWPORT, KENTUCKY, ASSIGNOR OF ONE-HALF TO THE HIGGIN MANUFACTURING COMPANY, OF NEWPORT, KENTUCKY, A CORPORATION OF WEST VIRGINIA.

WINDOW-VENTILATOR.

1,137,139.

Specification of Letters Patent. Patented Apr. 27, 1915.

Application filed April 16, 1914. Serial No. 832,152.

To all whom it may concern:

Be it known that I, HENRY HIGGIN, a citizen of the United States, and a resident of the city of Newport, in the county of Campbell and State of Kentucky, have invented certain new and useful Improvements in Window-Ventilators, of which the following is a full, clear, and exact description, reference being had to the accompanying drawings, forming part of this specification.

My invention has relation to window ventilators of the class wherein the ventilator is located between the sill of the window and the bottom of the sash and is designed to be opened by raising the sash, thereby admitting an indirect current of air into the room. It has special relation to window ventilators of the kind shown and described in my Letters Patent No. 1,064,730, issued June 17, 1913.

The object of the invention is to provide an effective means of adjustably mounting such a ventilator in windows so as to accommodate the variations of size in the frames of windows, and this without in any way interfering with the use of the ventilator, or leaving gaps between its sides and the window frames.

It has been the subject of much investigation and trial to devise a mounting means to answer this purpose. In the patent referred to, while the mounting is adjustable to a certain degree, there is only latitude for slight adjustment, and it can be appreciated that such a window ventilator for a window of certain general size would be rendered useless if because of the usual variation of the size of that window from the normal it could not be used.

I accomplish the purpose mentioned and certain other advantages which will be described by that certain construction and arrangement of parts to be hereinafter more specifically pointed out and claimed.

In the drawings, Figure 1 is an elevation of the ventilator and window taken from the outside, in raised position. Fig. 2 is a perspective view of one end of the ventilator in place, taken from the outside. Fig. 3 is a perspective view of the end wall and attaching means, being the ones shown in Fig. 2, but removed from the window and turned half way around. Fig. 4 is a vertical section taken just inside of the end wall show-

ing the ventilator screen being removed for cleaning.

The window is of the ordinary type, having a sill 1, a sliding sash with a lower rail 2, and a bead 3 upon which the sash slides. The ventilator comprises a boxlike structure, having a bottom portion 4 and end walls 5. The end walls have inwardly extending flanges 6, 7, 8 and 9.

A pivoted side wall 10, having knobs 11, 65 for opening and closing the same is mounted within the box by means of a curved flange 12, inserted under the bead 13 formed in the bottom portion 4. The top edge of the wall 10 is provided with a bead 14, 70 which fits into a bead 15 formed at the meeting point of the flanges 6 and 7 of the end walls. This structure provides a weather-tight fit of the inner wall, and a means for holding the wall in its raised or closed position. For further details as to this construction, reference is made to the Letters Patent above mentioned.

The flanges 9 of the end pieces and the flanges 6 are cut away at 16 to leave an opening for inserting and withdrawing the screen 17 from the ventilator. The screen is formed of a perforated plate of the size of the box, having wire gauze secured to it if desired, and hooks 47 for connecting it 85 to the lower window sash.

In securing the box to the window, the bottom flanges 8 and the bottom pieces 4 are screwed to the window frame after the box is located in position.

Riveted or otherwise secured on the outer face of the end pieces are the angle plates 18. These plates have their upper edge 19 preferably on a level with the top flange of the end plates 5 and extending on a continuation of the plane of the flange 9 of the plates 5. They have, also, an inturned base flange 20 provided with a hole 21 for screwing them to the sill when properly positioned.

Angle plates 22 are provided for the purposes of mounting the ventilator box. These plates at their upper end have loops or turned flanges 23 to slide on the edges 19 of the plates 18. The inturned portions 24 105 of the plate 22 are adapted to be inserted under the bead 3 and screwed into place there (Fig. 2), or else countersunk into the face of the bead in the ordinary manner.

The laterally extending portions of the 110

plates 22 can be wide enough to meet all reasonable demands for adjustment; and the flange 23 should extend practically the whole width of the plates along the top edge. Now 5 since the plate 22 will slide on the plate 18, and since the flange extends the whole width of the plate 22, the latitude for adjustment without leaving any opening between the end plates and the window frame is equal 10 to substantially the entire width of the plate 22.

The manner of mounting the ventilator box is to place it in the desired position and then slide the plates 22 onto the edge of the 15 plates 18. The portions 24 of the former plates are then screwed in place and the bead brought down over them. Then the other bottom portions, as heretofore mentioned, are screwed into place.

20 It can now be seen that the adjustment of the mounting plates 22 is easy and of sufficient magnitude. The parts should not be mounted so that these plates interfere with the removing of the screen (Fig. 4) through 25 the flange openings at 16. If desired, the new mounting may be used on one side only and the end plate 5 at the other end screwed directly onto the window frame, as at the left side of Fig. 1 of the drawings.

30 To have a flange or loop similar to the loop 23 on the end plates themselves is not satisfactory, because to have any latitude for adjustment would require such an extension from the end plates as to render the 35 ventilator so equipped useless in any but abnormal situations because of being too long to fit. This difficulty is overcome by my structure.

Another advantage is that the loops 23 as 40 shown in this improved mounting give an additional support to the ventilator box. It is at the attachment side of the box that the window slides and such strain as is placed

on the box is applied directly at the point where the window brings the ends of the 45 screen 17 into contact with the flanges of the end pieces. If then the loops were on the end plates, none of the strain would be taken by the plates 22, which on the contrary would remain in place even if the entire box were torn away.

Having thus described my invention, what I claim as new and desire to secure by Letters Patent, is:—

1. In a device of the character described, 55 a ventilator box member, and means for securing the same in the frame of a window, comprising a plate secured to the said box member, said plate having a laterally extending portion for securing it to the box 60 member, a base portion for securing it to the window sill, and a vertical portion extending parallel with said sill, and a plate having a vertical member provided with means for slidably engaging the vertical member of the plate first mentioned, and a lateral member for securing it to the side of the window frame.

2. In a device of the character described, 70 a ventilator box member, and means for securing the same in the frame of a window, comprising a plate secured to the said box member, said plate having a laterally extending portion for securing it to the box member, a base portion for securing it to the window sill, and a vertical portion extending parallel with said sill, and a plate having a vertical member provided with a downwardly depending flange for slidably engaging the vertical member of the plate first 75 mentioned, and a lateral member for securing it to the side of the window frame.

HENRY HIGGIN.
